UNITED STATES PATENT OFFICE

2,579,075

POWER HAMMER

Charles A. Hirschberg, Mountain Lakes, N. J.

Application April 14, 1949, Serial No. 87,378

10 Claims. (Cl. 123—7)

1

The invention herein disclosed relates to power hammers of the type disclosed in the Charles A. Hirschberg Patent No. 2,446,830 of August 10, 1948, and co-pending patent application Serial No. 39,902 filed July 21, 1948, now Patent Number 2,545,999, granted March 20, 1951, and designed for such operations as rock drills, pavement breakers, pile drivers, tampers and the like.

Particularly the present invention is concerned with a hammer of the type disclosed in the patent application identified, wherein the hammer blow is struck by a free piston coupled by air cushion with an inner, crank connected piston.

Important objects of the present invention are to assure a proper air coupling between the pistons, when required to effect the cyclic operation of the machine, and to prevent this air coupling from interfering with or impairing the striking power of the outer piston.

Related objects are to provide simple and practical mechanism for automatically and effectively providing the necessary air coupling as such and for releasing this coupling and dissipating its cushioning effect on the power impulse stroke of the machine.

Special objects of the invention are to effect reductions in the weight and size of such machines, rendering them more suitable for portable, hand operation.

Other desirable objects attained by the invention will appear or are set forth in the following specification, broadly defining and claiming the invention.

The drawings accompanying and forming part of the specification illustrate certain present practical embodiments of the invention. Structure and arrangement of parts, however, may be further modified and changed as regards the immediate illustration, all within the true intent of the invention, as will appear from the breadth and scope of the following specification and claims.

Fig. 1 in the drawings is a vertical sectional view of the power hammer showing the pistons at top stroke and the drill rod indicated broken away;

Fig. 2 is an enlarged transverse sectional view across the plane of the intake and exhaust ports on substantially the line 2—2 of Fig. 1;

Fig. 3 is a broken vertical sectional view on a plane at right angles to that of Fig. 1;

Fig. 4 is an enlarged broken transverse sectional view through the compression chamber at the lower end of the working cylinder, on substantially the plane of line 4—4 of Fig. 3, inter-

2

secting the choker and air inlet valve and the fuel injection nozzle;

Figs. 5, 6 and 7 are broken sectional and somewhat diagrammatic views illustrating successive positions of the outer and inner pistons.

In the machine illustrated the working cylinder is designated 10, the outer, free piston 11, and the inner piston 12.

The latter is attached by connecting rod 13 with crank 14 of shaft 15 and necessary ports and connections are provided for operation of the machine as a two-cycle internal combustion engine and to provide, as needed, an air coupling cushion between the two pistons.

15 The outer, elongated piston 11 is shown as having a head 16 at the upper end cooperative with the cylinder head 17 to provide a combustion chamber, and a head 18 cooperative with the lower end 19 of the cylinder to form an air induction and mixture compression chamber and engageable with the anvil 20 to apply the striking force to the drill steel or other tool element 21.

20 The crankshaft 15 is shown journaled in position extending transversely and diametrically across the mid-length portion of the working cylinder and the long, outer piston is shown slotted at 22 in opposite sides to pass the crankshaft and in turn to be guided thereby.

25 Additionally, the outer piston is shown slotted at 23 in opposite sides in a plane at right angles to slots 22 to provide clearance for rotation of the crank and lower connecting rod bearing. This enables construction of the working cylinder in substantially cylindrical form and practically all of the same diameter.

30 The machine may be operated as a simple internal combustion engine with carburetor or fuel injection, or on the diesel or other approved cycle.

40 In the present illustration, air is taken into the compression chamber 24 through inlet ports 25 on the up-stroke of the lower piston head 18, fuel introduced through a lower port 26 by injection nozzle 27, and the mixture compressed 45 on the down-stroke of the piston and passed by transfer passage 28 to the intake ports 29, Figs. 1 and 2.

The intake of air into the lower compression chamber 24 is shown controlled by a check valve 50 in the form of a flat disc 30, loosely confined by a cage 31, Figs. 3 and 4, and arranged to close outwardly against an annular valve seat 32 in the air intake throat 33.

An externally controlled choke valve 34 is 55 shown pivotally adjustable in the air intake 33,

which may be set and adjusted by a quadrant lever or the like.

The intermediate crankcase portion of the working cylinder and interior of the outer piston are shown as open to atmosphere through a breather 35, Fig. 1. The air coupling and cushion between the two pistons is created, released and restored in the present disclosure, through porting connections between the pistons and working cylinder.

Specifically the inner piston 12 is shown as having a port 36 extending from the top, out through the side of the same and a port 37 below the top extending from inside, out through the skirt portion of this piston.

The outer piston is shown as having two generally similarly spaced ports 38, 39, therethrough to register at times with the inner cylinder ports 36, 37, at the inside, and with an elongated channel 40 in the cylinder wall at the outside.

This porting arrangement is such that at and about the end of the up-stroke, as shown in Fig. 5, the ports of the inner piston will lap those of the outer piston so that air confined in the air cushion space 41 between the top of the inner piston and inside of the upper piston will be fully compressed and provide the coupling necessary for enabling the outer piston to compress the combustible mixture in the combustion chamber 42 between the head of the outer piston and cylinder head 17.

This closed, staggered relation of ports continues for a time sufficient to permit transmission of proper impulse to the inner, engine forming piston 12 and the latter, accelerating under this impulse and expansion of air compressed in chamber 41, then carries ports 36 and 37 into registry with ports 38 and 39 at a time when the latter, in the outer piston 11, Fig. 6, are open to elongated channel 40 in the cylinder wall, thus to relieve the cushioning air to the inside of the pistons and the crankcase. The latter, being at atmospheric pressure, through breather 35, permits reduction of the air coupling cushion to atmospheric pressure and such registration of ports continues for sufficient time to dissipate the air cushion to such an extent as not to impair or reduce the striking force of the outer piston on the tool.

Due to impact with the tool, the outer piston has a shorter stroke than the inner, crank controlled piston and this, together with the factor of acceleration of the inner piston, assures non-impairment of the working stroke by any air cushion between the pistons.

At and about the moment of impact, due to higher speed of the inner piston, a partial vacuum may be created in the cushion chamber 41 between the pistons, with the inner piston thus actually assisting the outer piston in striking effect.

On return stroke of the two pistons, any partial vacuum created between the pistons will assist in restoring the air cushion at 41 as soon as the ports 36, 37, in the inner piston approach registration with ports 38, 39, in the outer piston and the latter come into registration with the cylinder channel 40, as will be understood from consideration of Fig. 7. Air then trapped in chamber 41 between the two pistons constitutes the cushion for preventing metal-to-metal contact between the pistons and communicating the force necessary for compression of the mixture in the combustion chamber.

Acceleration resulting from rebound of the 75

free piston also may assist in creating the partial vacuum between the pistons required to replenish the air cushion coupling between the pistons.

As a result of the construction and arrangement described, an air cushion is provided which at the moment of explosion prevents metal-to-metal contact between the free piston and the crank controlled piston. Acceleration of the inner, crank connected longer stroke piston resulting partly from expansion of this highly compressed air cushion, causes the inner piston to lead the outer piston, resulting in alignment of the piston ports at a time when these ports are in register with the channel 40 in the cylinder, with consequent release of the cushioning air from chamber 41 into the crankcase, Fig. 6. Discharge of the confined air cushion enables the outer piston to strike an accelerated blow on the tool or other part, possibly assisted by tendency of the leading piston to create partial vacuum between the pistons at this time.

This automatic release of the air cushion prior to impact enables the free piston to apply maximum force.

As the piston ports register with each other and with the channel in the cylinder wall, air from the crankcase at atmospheric pressure, possibly assisted by partial vacuum created between the pistons, enters the cushion chamber 41, thus automatically restoring the air coupling between these pistons and enabling the inner piston under compulsion of the crank, to carry the outer, free piston to the full top of the compression stroke, as in Fig. 5.

This automatic release and restoration of the air cushion and coupling is of advantage in facilitating internal cooling and lubrication of the parts. The breather 35, while opening the crankcase portion of the machine to atmosphere, may be designed to prevent escape of lubricant so that all internal parts can be properly lubricated.

The lower or inner end of the free piston, in addition to forming a hammer, operates with air pump effect to draw air into compression chamber 24 and to compress such air mixed with fuel injected by nozzle 27 and transfer the combustible mixture through passage 28 to intake port 29. Passage 28 may be formed as a channel cored in the wall of the cylinder, as indicated in Fig. 1.

To effect the pumping operation described and to perform necessary intake and exhaust valve functions, the outer, free piston should be assured full stroke operation even in the event of ignition failure.

Accordingly, a piston follower may be provided, as illustrated in Figs. 5, 6 and 7, and embodying in this case a tubular plunger 43 operating through the cylinder head in a guide 44 and bearing at its inner end on the head of the free piston under pressure of an enclosed spring 45. A bleeder hole 46 is shown in the side of the tubular guide 44 to release air trapped in the tubular follower, and this relief opening may be located so as to be controlled by the plunger 43, as indicated in Figs. 5 and 6, for holding a certain amount of trapped air as an air cushion assisting operation of the follower spring 45.

The piston follower construction is not shown in Figs. 1 and 3, but it will be appreciated that when employed it may be centrally located, as shown in Figs. 5, 6 and 7, and the spark plug 47, Figs. 1 and 3, be located to one side instead of at the center of the cylinder head.

In addition to preventing short stroking of the

free piston and assuring proper valving and pumping action, the spring follower aids in the starting of the engine by effecting full valving and pumping strokes of this piston when the engine is being turned over at slower, starting speeds. The head of the outer piston may be designed with a baffle 48, Fig. 1, as customary in two-cycle engines, to prevent direct passage from the intake ports 29 at one side, across to the exhaust ports 49 at the opposite side of the cylinder.

The shape and size of the cushion chamber 41 between the pistons may be determined by an inner head or wall of the outer piston head, as indicated at 50 in Figs. 1 and 3, or this inner surface may be an integral wall of the piston head, as indicated in Figs. 5, 6 and 7.

In either case the main piston head 16 may have a removable screw mounting in the piston, as indicated at 51, to facilitate assemblage of the parts.

The fuel injector 27 may be connected with a suitable fuel pump 52 operated by the engine, after the manner indicated in Fig. 3. Other engine driven accessories may be provided, as needed, in line with conventional practice.

What is claimed is:

1. A machine of the power hammer type comprising a working cylinder having combustion and compression chambers in opposite ends of the same, a free piston in said cylinder having heads at opposite ends operating in said combustion and compression chambers, respectively, the combustion chamber portion of said cylinder having intake and exhaust ports and the compression chamber portion of said cylinder having an air admission port controlled by said piston heads, a fuel injector for said compression chamber, a transfer passage extending from said compression chamber to said intake port, a crank-shaft journaled across said working cylinder, an inner piston operating in said free piston and connected with said crankshaft and porting connections between said pistons and working cylinder cooperative to provide a cushion of air between said pistons on the out-stroke of the same and to release cushioning air between the pistons on the inward, power stroke of said pistons, including longitudinally spaced ports in each of said pistons arranged to register at a part-stroke position of said pistons and to be out of register in the full-stroke positions of said pistons and a transfer channel in the wall of the cylinder for connecting the spaced ports in the registering relation of the same in said part-stroke position of the pistons.

2. A machine of the power hammer type comprising a working cylinder having combustion and compression chambers in opposite ends of the same, a free piston in said cylinder having heads at opposite ends operating in said combustion and compression chambers, respectively, the combustion chamber portion of said cylinder having intake and exhaust ports and the compression chamber portion of said cylinder having an air admission port controlled by said piston heads, a fuel injector for said compression chamber, a transfer passage extending from said compression chamber to said intake port, a crank-shaft journaled across said working cylinder, an inner piston operating in said free piston and connected with said crankshaft and porting connections between said pistons and working cylinder cooperative to provide a cushion of air between said pistons on the out-stroke of the same and to release cushioning air between the

pistons on the inward, power stroke of said pistons, and a follower for causing the free piston to follow inward movement of the crank connected piston.

3. A machine of the power hammer type comprising a working cylinder having combustion and compression chambers in opposite ends of the same, a free piston in said cylinder having heads at opposite ends operating in said combustion and compression chambers, respectively, the combustion chamber portion of said cylinder having intake and exhaust ports and the compression chamber portion of said cylinder having an air admission port controlled by said piston heads, a fuel injector for said compression chamber, a transfer passage extending from said compression chamber to said intake port, a crank-shaft journaled across said working cylinder, an inner piston operating in said free piston and connected with said crankshaft and porting connections between said pistons and working cylinder cooperative to provide a cushion of air between said pistons on the out-stroke of the same and to release cushioning air between the pistons on the inward, power stroke of said pistons and a spring follower acting on the combustion chamber head of the free piston.

4. A machine of the power hammer type comprising a working cylinder having combustion and compression chambers in opposite ends of the same, a free piston in said cylinder having heads at opposite ends operating in said combustion and compression chambers, respectively, the combustion chamber portion of said cylinder having intake and exhaust ports and the compression chamber portion of said cylinder having an air admission port controlled by said piston heads, a fuel injector for said compression chamber, a transfer passage extending from said compression chamber to said intake port, a crank-shaft journaled across said working cylinder, an inner piston operating in said free piston and connected with said crankshaft and porting connections between said pistons and working cylinder cooperative to provide a cushion of air between said pistons on the out-stroke of the same and to release cushioning air between the pistons on the inward, power stroke of said pistons, including longitudinally spaced ports in each of said pistons arranged to register at a part-stroke position of said pistons and to be out of register in the full-stroke positions of said pistons and a transfer channel in the wall of the cylinder for connecting the spaced ports in the registering relation of the same in said part-stroke position of the pistons, a check valve for holding air drawn into said compression chamber and a choker valve for governing supply of air to said check valve.

5. A machine of the power hammer type comprising a working cylinder having combustion and compression chambers in opposite ends of the same, a free piston in said cylinder having heads at opposite ends operating in said combustion and compression chambers, respectively, the combustion chamber portion of said cylinder having intake and exhaust ports and the compression chamber portion of said cylinder having an air admission port controlled by said piston heads, a fuel injector for said compression chamber, a transfer passage extending from said compression chamber to said intake port, a crank-shaft journaled across said working cylinder, an inner piston operating in said free piston and connected with said crankshaft and port-

ing connections between said pistons and working cylinder cooperative to provide a cushion of air between said pistons on the out-stroke of the same and to release cushioning air between the pistons on the inward, power stroke of said pistons, the inner piston having a head and skirt and said porting connections including a port opening down through the head and out through the side of the inner piston, a port extending through the skirt of said inner piston, through ports in the wall of the outer piston to register with said ports in the inner piston and a longitudinal channel in the wall of the cylinder of a length to bridge the space between the ports in the outer piston and disposed to accomplish such bridging action at a part-stroke position of said pistons.

6. A power hammer of the internal combustion type comprising a working cylinder, a free piston operating therein, a crank controlled piston operating in said free piston and porting connections between said pistons and working cylinder for automatically creating an air coupling and cushion between said pistons in one phase of the engine cycle and for releasing cushioning air between the pistons in the power stroke phase of the engine cycle, including a longitudinal channel in the working cylinder located at a part-stroke position of the pistons, longitudinally separated ports through the outer piston spaced to be connected by said channel, longitudinally separated ports in the inner piston spaced to register with the spaced ports of the outer piston and the working cylinder including a crankcase portion open to atmosphere and in communication with said porting connections.

7. A power hammer of the internal combustion type comprising a working cylinder, a free piston operating therein, a crank controlled piston operating in said free piston and porting connections between said pistons and working cylinder for automatically creating an air coupling and cushion between said pistons in one phase of the engine cycle and for releasing cushioning air between the pistons in the power stroke phase of the engine cycle, including a longitudinal channel in the working cylinder located at a part-stroke position of the pistons, longitudinally spaced ports through the outer piston, spaced to be connected by said channel during a predetermined portion of the stroke of said piston, and ports in the side of the inner piston to register with said ports in the outer piston, one of said inner piston ports being open to space between the two pistons for containing the cushioning air.

8. A power hammer of the internal combustion type comprising a working cylinder, a free piston operating therein, a crank controlled piston operating in said free piston and porting connections between said pistons and working cylinder for automatically creating an air coupling and cushion between said pistons in one phase

of the engine cycle and for releasing cushioning air between the pistons in the power stroke phase of the engine cycle, said working cylinder having intake and exhaust ports controlled by said outer piston and a spring follower acting on said outer piston to enforce full port opening movement of the same.

9. A power hammer of the internal combustion type comprising a working cylinder, a free piston operating therein, a crank controlled piston operating in said free piston and porting connections between said pistons and working cylinder for automatically creating an air coupling and cushion between said pistons in one phase of the engine cycle and for releasing cushioning air between the pistons in the power stroke phase of the engine cycle, said working cylinder having a crankcase portion open to atmosphere and said porting connections being open to said crankcase portion of the cylinder and including longitudinally separated ports in both pistons spaced to register in a part-stroke position of the pistons and a connecting channel in the working cylinder of greater length than the spacing of said ports.

10. A power hammer of the internal combustion type comprising a working cylinder, a free piston operating therein, a crank controlled piston operating in said free piston and porting connections between said pistons and working cylinder for automatically creating an air coupling and cushion between said pistons in one phase of the engine cycle and for releasing cushioning air between the pistons in the power stroke phase of the engine cycle, said working cylinder having a combustion chamber at one end and a compression chamber at the opposite end, the outer piston having piston heads operative in said chambers, the compression chamber having an air inlet and a transfer passage extending from said compression chamber to said combustion chamber and controlled at said latter chamber by said outer piston and said porting connections including longitudinally separated ports in said pistons spaced to register in a part-stroke position of the pistons, one pair of said registering ports communicating with the space between the pistons and the other pair of registering ports communicating with the space inside the inner piston and the working cylinder having a longitudinal channel for connecting the registering ports in said part-stroke position of the pistons.
